UNITED STATES PATENT OFFICE.

HENRY AUGUST WERNECKE, OF MANITOWOC, WISCONSIN.

HEATING AND VENTILATING SYSTEM.

No. 893,961.

Specification of Letters Patent.

Patented July 21, 1908.

Application filed January 7, 1908. Serial No. 409,651.

To all whom it may concern:

Be it known that I, HENRY AUGUST WERNECKE, a citizen of the United States, and a resident of Manitowoc, in the county of Manitowoc and State of Wisconsin, have invented a new and improved Heating and Ventilating System, of which the following is a full, clear, and exact description.

This invention relates to certain improvements in heating and ventilating systems adapted for use in school-rooms and the like, and relates more particularly to the means for automatically establishing the desired circulation of the air, the withdrawal of the foul air, and the supplying of fresh air.

In a system embodying my invention, the air and smoke conduits are so arranged that the foul air leaving the room adjacent the floor, is heated by the heat of the gaseous products of combustion, so as to establish an upward current of the foul air, and one object of the invention is to utilize a portion of the space intermediate the walls as a portion of the foul air conduit, and to provide a drum within the room adjacent the ceiling, connecting with said space within the walls and surrounding a portion of the smoke pipe, whereby said foul air is heated.

In the preferred arrangement for employing my system, a stove is provided having an air conduit in conjunction therewith, the outlet from said air conduit delivering to the room, and the inlet to said conduit having damper-controlled branches, one of which takes in air from adjacent the floor and the other of which may take in air from the outside of the building. The smoke or gaseous products of combustion from the stove pass from the stove through a stove-pipe entering the chimney adjacent the ceiling, and a horizontal portion of this stove pipe is surrounded by a drum forming a portion of the air conduit for the escape of the foul air, another portion of this foul air conduit being adjacent the floor.

Reference is to be had to the accompanying drawings, forming a part of this specification, in which similar characters of reference indicate corresponding parts in all the figures, and in which

Figure 1 is a perspective view of a portion of a room having an apparatus designed for carrying out my improved system; Fig. 2 is a transverse section through the wall, chimney and drum; Fig. 3 is a vertical section on the line 3—3 of Fig. 2; and Fig. 4 is a side eleva-

tion of the stove and the fresh air conduit, a portion thereof being shown in section.

My improved system is especially designed for use in connection with school-rooms, 60 halls, and the like, heated by stoves, although it may be employed wherever a heating of the air and an automatic circulation thereof is desired. The special stove 10, which I have illustrated for facilitating the 65 heating and circulating of the fresh air, is provided with an air chamber 11 at the rear side thereof, having an inlet conduit provided with two damper-controlled branches 12 and 13. The branch 12 extends through the wall 70 14 of the building to the outside thereof, and the branch 13 terminates adjacent the floor. An outlet conduit 15 from the air chamber 11 extends inwardly from the upper portion 75 of the latter to the interior of the stove, and then extends upwardly and discharges into the room adjacent the top of the stove. Directly above the air chamber 11, the stove pipe 16 or conduit for the gaseous products of combustion, extends outwardly from the 80 stove laterally and then upwardly toward the ceiling. Fresh air may enter the branch 12 to the air chamber and thence be discharged into the room through the conduit 15, or the colder air adjacent the floor may 85 be taken in through the branch 13 to the air chamber 11 and discharged into the room through the conduit 15. In other words, an automatic circulation of the air is established by the upward movement of the heated air 90 within the air chamber and the conduit 15. The dampers in the branches 12 and 13 may be adjusted to take in the air from the desired source.

The wall or partition 17 of the room is preferably formed of vertically-disposed studing 18, having lath and plaster, or other suitable covering upon opposite sides thereof, whereby the space intermediate the sides forms vertically-disposed conduits, and one of these conduits is preferably employed as a portion of the outlet conduit for the foul air. As shown, the space between two of the studs forms a conduit 19, at the lower end of which is a foul air inlet 20, covered by a reticulated metal plate to prevent the entrance of large foreign bodies. A suitable brick chimney is provided, preferably, subdivided into two conduits or passages, one conduit or passage 21 for the gaseous products of combustion and the other passage 22 for the foul air. The stove-pipe 16 extends upwardly

from the stove to adjacent the ceiling and then extends horizontally along the wall 17 past the conduit 19 to the chimney passage 21. The portion of the stove-pipe 16 intermediate the conduit 19 and the conduit or passage 22 is inclosed by a drum 23, connected by an elbow 24 at one end to the conduit 19 and connected by an elbow 25 at the opposite end to the conduit or passage 22 in the chimney. The chimney conduit or passage 22 also communicates at its lower end with the interior of the room by an air inlet 26, normally covered by a reticulated metal plate. The foul and colder air adjacent the floor may enter both the inlets 20 and 26, and that entering the inlet 20 pass upward within the wall of the room to the elbow 24, then through the drum 23 and elbow 25 to the chimney passage 22. The air within the drum becomes heated from the heat of the smoke in the stove-pipe 16, and as the upper outlet end of the passage 22 is open to the atmosphere and this passage is larger than the conduit 19 within the walls, an upward circulation of air is established through the conduit 19 and drum 23 to the passage 22. By means of this arrangement, all parts of the foul air conduit save the drum 23 and its connections, are concealed from view, and the drum is adjacent the ceiling, where it does not interfere with the free use of the room. The stove-pipe passes directly from the stove to the chimney and does not engage

with the wall at any part, save where it passes through into the chimney; thus the liability of setting fire to the building from the heated pipe is avoided, and the air which does pass within the wall is that which has been heated. The air after leaving the passage 19 and after being heated in the drum 23, passes to the brick chimney where there is no danger of setting fire to the walls.

Having thus described my invention, I claim as new and desire to secure by Letters Patent:

In a heating and ventilating system for rooms, the combination of a foul air escape conduit, including a drum adjacent the ceiling of the room, two vertically-disposed passages within the walls of the room, one of said passages communicating with one end of the drum and with the room adjacent the floor thereof, and the other of said passages communicating with the opposite end of said drum and with the outside atmosphere, the last-mentioned passage being formed of non-combustible material, a stove within said room, and a stove-pipe extending therefrom and through said drum.

In testimony whereof I have signed my name to this specification in the presence of two subscribing witnesses.

HENRY AUGUST WERNECKE.
